THOMAS MIDGLEY, JR., OF DAYTON, OHIO, ASSIGNOR, BY MESNE ASSIGNMENTS, TO
GENERAL MOTORS RESEARCH CORPORATION, OF DAYTON, OHIO, A CORPORATION
OF DELAWARE.

HYDROGENATION FURNACE.

Application filed October 5, 1918. Serial No. 256,952.

To all whom it may concern:

Be it known that I, THOMAS MIDGLEY, Jr., a citizen of the United States of America, residing at Dayton, county of Montgomery, 5 and State of Ohio, have invented certain new and useful Improvements in Hydrogenation Furnaces, of which the following is a full, clear, and exact description.

This invention relates to hydrogenation 10 and more particularly to a method of hydrogenation adapted for the preparation of fuels from unsaturated hydrocarbons and to an apparatus for carrying that method into effect.

15 The principal object of the invention is to provide an improved method of hydrogenation which is especially efficient in that the materials entering into the reaction chamber are fed into the apparatus continuously 20 under pressure so that continuous operation is effected, and to provide improved apparatus for carrying that method into effect.

Other objects and advantages of the present invention will be apparent from a 25 description thereof set out below.

This method of hydrogenation and the apparatus for carrying it into effect have been especially designed for hydrogenating benzene to produce cyclohexane, or mixtures of 30 benzene and cyclohexane containing these two constituents in any desired proportions. It is not, however, limited to the hydrogenation of benzene inasmuch as it is adapted for hydrogenation generally.

35 In hydrogenation in the gaseous phase, as heretofore carried on, the reaction has been intermittent. That is a mixture of hydrogen and the vaporized material to be hydrogenated has been forced into the reaction 40 chamber and over the catalytic material under the desired pressure, the hydrogen and vaporized material associated therewith being handled in small charges, each charge being fed to the reaction chamber and completely 45 acted upon before the next charge is introduced. In my method the mixture of hydrogen and the vaporized material to be hydrogenated is fed into the reaction chamber and over the catalytic material 50 therein continuously, the desired pressure within the reaction chamber being maintained at all times by feeding the mixture of hydrogen and vaporized material at this pressure. It is quite obvious that such a 55 method of hydrogenation is decidedly ad-

vantageous and that much better results will be obtained than with the intermittent methods heretofore practiced. For carrying this method into effect I make use of the apparatus illustrated in the accompanying drawing 60 in which—

Fig. 1 represents a preferred embodiment of a form of apparatus used by me; and

Fig. 2 represents a modified form of reaction chamber, adopted as a substitute for 65 the reaction chamber illustrated in Fig. 1.

In the drawing, like characters of reference designate like parts throughout the several views thereof.

Referring to Fig. 1, 10 is a reaction chamber having the lower end permanently closed and the upper end closed by means of a removable cover 11 held tightly in place by any desired means. Leading into the chamber 10 is an inlet pipe 12 adapted to supply 70 thereto a mixture of hydrogen and the vaporized material to be hydrogenated. The inlet pipe 12 is connected to a chamber 13 adapted to receive vaporized benzene, or other vaporized material to be hydrogenated, and hydrogen. 75 Leading into the chamber 13 is a supply pipe 15 through which the material to be hydrogenated is forced at any desired pressure by means of the pump 16.

80 Cooperating with the pipe 15, adjacent the chamber 13, is a gas heater 14 adapted to heat a section of the pipe to vaporize any benzene or other material passing therethrough. This heater and the pipe associated therewith are inclosed in a muffle 17, shown as partly broken away, the arrangement being such that any desired temperature may be used in carrying on the vaporization. By proper regulation of the pump 85 the pressure at which the vaporized material is forced into the chamber 13 may be maintained constant. Any other desired means may be used for vaporizing the benzene or other material to be hydrogenated. For example this material may be passed through pipes heated by a lead bath, or it may be passed over coils heated by steam. It is merely necessary that the material be in 90 vaporous form when passing through the reaction chamber. Associated with the pump 95 16 is a pressure regulated throttle valve 18, responsive to variations of pressure within the pipe 15 and adapted to vary the supply of steam, or other operating fluid, to the 100 110

pump 16 to maintain a continuous pressure within the pipe 15, and thus to maintain continuous the pressure under which the material to be hydrogenated is sprayed into 5 the chamber 13. Leading into the chamber 13 is a second supply pipe 20 through which hydrogen is admitted thereto. This pipe is connected to a storage tank 21 which is kept supplied with hydrogen under any desired 10 pressure by means of a pump 22. Cooperating with the pump 22 is a pressure operated throttle valve 23 responsive to variations in pressure within the delivery pipe 20 and adapted to vary the operation of the 15 pump 22 to maintain constant, and at any desired pressure, the pressure within the storage chamber 21. From the structure thus described it is obvious that a mixture of hydrogen and vaporized material to be 20 hydrogenated is fed continuously under any desired pressure from the chamber 13 through the pipe 12 into the interior of the hydrogenation furnace or reaction chamber 10.

25 Carried by the inner wall of the chamber 10 is a shelf or ridge 25 adapted to support a cartridge 26, the cartridge having a flange around the upper end thereof cooperating with said shelf. Between this flange and 30 the shelf is a gasket 27, of any desired material, adapted to prevent the passage of any of the hydrogen or vaporized material between the walls of the reaction chamber and the cartridge so that all of the hydrogen 35 and vaporized material will pass through the catalytic material. The cartridge 26 consists of a seamless tube adapted to contain catalytic material 28. In the hydrogenation of benzene I have found a catalyst of nickel 40 oxide to give very satisfactory results, but of course other catalysts may be used as conditions may demand. For holding the catalytic material within the cartridge it is closed by a previous plate 29 held in place 45 by an internal flange around the lower end thereof. By providing a catalyst container of this sort, capable of ready removal through the upper end of the reaction chamber, the changing of catalytic material is 50 greatly facilitated and, what has been heretofore a difficult and tedious job requiring a lengthy shut-down in operation, is made considerably easier, the entire change, which 55 consists in removing the cartridge containing the spent catalyst and substituting therefor a cartridge containing a fresh catalyst, being accomplished in a few minutes without requiring cooling off of the reaction chamber, and without interfering hardly at 60 all with operation.

Surrounding the reaction chamber 10 are a number of resistance or heating coils 30 each coil being connected by means of suitable conductors 31 with any desired source 65 of electrical current, (not shown). Coop-

erating with each heating coil 30 is a switch 32 adapted to control flow of current through such coil, to thus control the heating effect of the coil. The turns of each coil are insulated from each other, and the coils themselves are insulated from each other, by means of any desired insulating material. As shown, the wires constituting these coils are embedded in an insulating layer 33 of alundum. The specific type of 70 insulating material, however, is immaterial, other materials being capable of functioning satisfactorily.

An additional control of the temperature within the reaction chamber may be effected 80 by a control of the radiation of heat therefrom. For this purpose the chamber carrying the heating coils is covered with heat insulating material. Any desired type of 85 heat insulating material may be used but in my work I have found such material as asbestos or magnesia to be very satisfactory. As shown in Fig. 1 of the drawing the heating coils cover that part of the reaction 90 chamber containing the catalytic material, and the heat insulating material is preferably made up in the form of semi-cylindrical sections 35, two cooperating sections being adapted to completely enclose a definite 95 length of the reaction chamber. As shown, each pair of these semi-cylindrical sections is of sufficient length to enclose that part 100 of the reaction chamber surrounded by a complete heating coil. In the type of apparatus illustrated three heating coils are shown and three sections of insulating material are shown cooperating therewith. I prefer to construct these semi-cylindrical sections in the form of doors 35, supported 105 by hinges 36. This construction permits of securing a nice control of heat conditions within the chamber 10. Any number of 110 heating coils and insulating sections other than the number shown may be used if desired, a greater number permitting a nicer 115 control, and a smaller number less control of heat conditions.

Hydrogenation always takes place most favorably, for any particular material, within a certain definite temperature range. In 115 order that this temperature within the reaction chamber may be attained, during initial operation of the apparatus, it is necessary to completely close the heat insulating doors 35 and to pass an electric current through 120 each of the heating coils 30. When the desired temperature has been attained and the hydrogenation reaction is proceeding satisfactorily the heat of reaction will be considerable, and generally, as in the hydrogenation of benzene, more than sufficient to maintain the reaction. If the heat insulating doors 35 are maintained in closed position 125 temperatures will be reached which will tend to prevent effective carrying on of the 130

reaction because of dehydrogenation. After hydrogenation is fairly under way therefore heat from the coils is generally no longer necessary and consequently the current flowing therethrough may be interrupted. In addition it frequently becomes necessary to open the heat insulating doors in order to permit the dissipation into the atmosphere of some of the excess heat generated by the reaction. As stated above this apparatus was devised particularly for the hydrogenation of benzene, to secure either cyclohexane or a mixture of benzene and cyclohexane in any desired proportions. In the hydrogenation of benzene I have found that pressures of approximately 300 pounds per square inch and a temperature of substantially 300° centigrade maintained within the reaction chamber give very satisfactory results. Any substantial variation above or below this temperature results in a loss of efficiency.

For determining the temperature within the reaction chamber I make use of thermo-couples 40, which may be of any desired materials, a plurality of thermo-couples being used, not less than one to each heating coil being desirable, which are embedded directly in the wall of the reaction chamber. Each of these thermo-couples is connected with a switch 41 all of the switches being connected to a potentiometer. As shown in the drawing, the poles of the switches are connected direct to the potentiometer in parallel, a separate switch being provided for each thermo-couple. In order to determine the temperature of that part of the reaction chamber cooperating with the particular thermo-couple it is merely necessary to close the switch connecting the said thermo-couple with the potentiometer. The potentiometer may, if desired, be calibrated to read temperatures direct, but if not so calibrated it is quite easy to determine actual temperatures from the potentiometer readings.

By means of this temperature indicating device it is a very simple matter to determine the heat conditions within any particular part of the reaction chamber and, by means of the heating coils and the heat insulating doors, to maintain the desired heat conditions within such reaction chamber.

Leading off from the bottom of the reaction chamber 10 is an outlet pipe 50 which leads into a condenser 51 in which any vaporous material passing out of the reaction chamber will be condensed and will drain off through the pipe 52 into the collecting trap 53. Leading off from the trap 53 is a pipe 54, flow through which is controlled by means of the float operated valve 55. When the level of the liquid within the trap 53 rises to a predetermined height the float operated valve 55 will be opened to allow the escape of liquid therefrom until said valve is again seated. This pipe 54 leads

into a collecting or storage tank 56. Located in the pipe 54 is a valve 57 for controlling the flow of fluid therethrough into the tank 56. Leading off from the pipe 54 is a pipe 58 flow through which is controlled by means of the valve 59. The pipe 58 leads into a sampling tube 60 containing a hydrometer 61. If it is desired to determine the character of the fluid resulting from the hydrogenation within the chamber 10 it is merely necessary to close the valve 57 and open the valve 59 whereupon fluid flowing from the trap 53 will pass into the sampling tube 60 where its specific gravity may be read directly by means of the hydrometer 61. Where benzene is being hydrogenated to form a mixture of cyclohexane and benzene, such a mixture for instance as is described in my copending application Serial No. 256,874 filed Oct. 4, 1918, it is quite easy to determine by means of the hydrometer whether the mixture coming off from the reaction chamber is of the proper consistency and if not to alter operating conditions to secure the desired mixture. With this apparatus benzene may be hydrogenated completely into cyclohexane, or into any desired proportion of benzene and cyclohexane. To control the degree of hydrogenation it is merely necessary to vary the rate at which the benzene is fed to the reaction chamber, the faster it is fed thereinto the less time it is subjected to hydrogenating conditions and the smaller the percentage which is changed. Obviously by feeding the benzene slower or faster the time of reaction may be varied to secure any desired degree of hydrogenation, and the sampling tube and hydrometer permit of determining directly what the degree of hydrogenation is so that the rate of feeding may be intelligently controlled. Of course this is true in the hydrogenation of materials other than benzene.

Leading off from the condenser 51 is a recirculating pipe 70, the other end of which opens into the upper end of the reaction chamber 10. Any hydrogen that may pass off from the reaction chamber into the condenser 51 will be returned through this recirculating pipe to the upper end of the reaction chamber where it will again take part in the reaction going on therein. Surrounding the recirculating pipe 70, adjacent the place where it opens into the upper end of the chamber 10, is a condenser consisting of a chamber 71 having inlet and outlet pipes 72 and 73 through which water or other cooling fluid is supplied thereto. That portion of the recirculating pipe cooperating with this condenser is so inclined that any condensate therein will run back into the reaction chamber 10. The object of this condenser is to condense any vapor that may tend to flow from the upper end of the re-

action chamber through the recirculating pipe.

In Fig. 2 of the drawing I have illustrated a reaction chamber of a modified form. As illustrated the reaction takes place in a chamber 80 which is open at both ends, the upper end being closed by means of a removable cap 81 through which opens an inlet pipe 82, corresponding to the inlet pipe 12 of Fig. 1 and adapted to cooperate with just such a vaporizing chamber and supplying means as illustrated in Fig. 1. Also opening into the reaction chamber through the cap 82 is the upper end of a recirculating pipe 83, the functions of which are similar to those described in connection with the recirculating pipe shown in Fig. 1. The lower end of the reaction chamber is closed by means of a removable cap 87 having upwardly standing lugs 86 thereon adapted to support a perforated plate 84 which in turn supports a metallic cartridge 88 containing catalytic material 85. Carried by the inner wall of the reaction chamber is a shelf or ridge 89, and located between the lower surface of the shelf or ridge and the upper part of the cartridge 88 is a packing 90. In assembling, the cartridge 88 is inserted into the reaction chamber with the upper end of the frame 30 work abutting the packing 90 which is in turn in contact with the ridge 89. The perforated plate 84 is now inserted and the cap 87 placed in position with the lugs 86 thereof in contact with the said plate. As the bolts 91 are tightened the cap 87 is forced upwardly carrying the plate 84 with it. The cartridge 88 is thus forced against the packing 90 compressing such packing against the cooperating ridge 89 to form a 40 tight joint adapted to prevent the passage of any of the hydrogen or vaporized material between the wall of the reaction chamber and the cartridge 88, so that all of the hydrogen and vaporized material will pass through the catalytic material.

Leading off from the bottom of the reaction chamber is an outlet pipe 100 which leads into a condenser 101 having an outlet pipe 102 leading therefrom into a trap and 50 collecting mechanism similar to that disclosed in Fig. 1.

Surrounding the reaction chamber is a heating coil 95. As illustrated this heating coil consists of a pipe through which steam or other heating material is adapted to be circulated to secure the desired temperature within the chamber. It is obvious that this type of apparatus does not lend itself to such a nice and accurate control of heat conditions within the reaction chamber as does the type of apparatus illustrated in Fig. 1. This type of apparatus is, however, effective and quite satisfactory under general operating conditions.

From the above description the operation

of this device is thought obvious. Hydrogen, under pressure, is fed from the tank 21 through the chamber 13 to the reaction chamber. At the same time the material to be hydrogenated is vaporized and passed 70 into the chamber 13 under pressure substantially the same as that of the hydrogen. In actual practice it is generally preferable to float the chamber 13 and reaction chamber on the hydrogen line and inject the material to be hydrogenated thereinto at a pressure slightly in excess of the pressure of the hydrogen. The mixed hydrogen and vaporized material passes downwardly through the cartridge and catalytic material contained 75 therein. The reaction chamber, including the catalytic material, is maintained at the temperature necessary for securing the most efficient reaction by means of the heating coils and cooperating heat insulating doors. As stated above the degree of hydrogenation is varied by varying the period during which the material to be hydrogenated is exposed to the catalytic material in the presence of hydrogen. The vaporized hydrogenated material, along with any uncombined hydrogen, passes into the condenser 51 where the vaporized material condenses and flows into the trap 53 and from there to the collecting tank 56. The 80 uncombined hydrogen returns through the recirculating pipe 70 to the top of the reaction chamber whence it again passes through the catalytic material to take part in the reaction. The mode of operation of the modified form of reaction chamber shown in Fig. 2 is practically the same.

It is obvious from the above description that I have invented an efficient method of hydrogenation, and one which lends itself to great economy of operation. It is further obvious that I have devised apparatus for carrying that method of hydrogenation into effect which is not only very efficient and effective but is also comparatively simple in construction and lends itself to easy operation.

While the method herein described, and the forms of apparatus for carrying that method into effect, constitute preferred embodiments of the invention, it is to be understood that the invention is not limited to this precise method and these forms of apparatus, and that changes may be made in either without departing from the scope of 115 the invention which is defined in the appended claims.

What I claim is as follows:

1. The method of hydrogenating benzene which consists in introducing hydrogen and 125 benzene vapor into the presence of catalytic material, the hydrogen and benzene both being introduced continuously under pressure.

2. In a hydrogenation apparatus, a reac- 130

tion chamber adapted to contain catalytic material; a heating jacket associated therewith, said jacket comprising a plurality of units capable of separate operation to heat the whole chamber or any desired part thereof.

3. In a hydrogenation apparatus, a reaction chamber adapted to contain catalytic material; a heating jacket associated therewith and so arranged as to heat the whole chamber or any part thereof; and means associated with the chamber and the jacket for varying the intensity of the heating effect of the jacket upon the chamber.

15 4. In a hydrogenation apparatus, a reaction chamber adapted to contain catalytic material; a heating jacket therefor; and means associated with the chamber and the jacket for varying the intensity of the heating effect of the jacket upon the chamber, said means consisting of a plurality of units, arranged to control the radiation of heat from the jacket away from the chamber.

25 5. In a hydrogenation apparatus, a reaction chamber adapted to contain catalytic material; heating means therefor, said means comprising a plurality of units capable of simultaneous or separate operation to heat the whole chamber or any desired part thereof; and means comprising a plurality of units adapted to coat with the heating units to control the amount of heat lost by radiation away from the chamber.

35 6. In a hydrogenation apparatus, a reaction chamber adapted to contain catalytic material; heating means associated therewith adapted to heat the whole chamber or any part thereof; heat insulating means associated with the chamber and heating

means, adapted to heat insulate the whole 40 chamber or any part thereof; and means for accurately determining the temperature of any part of the chamber.

7. In a hydrogenation apparatus, a reaction chamber adapted to withstand high internal pressures, an inlet thereinto, and outlet therefrom; a condenser connected to said outlet; and a recirculating pipe leading directly from said condenser to the upper end of said chamber.

45 8. In a hydrogenation apparatus, a reaction chamber, an inlet thereinto, an outlet therefrom; a condenser connected to said outlet; a recirculating pipe leading from said condenser to the upper end of said chamber; and a second condenser surrounding the upper end of said recirculating pipe.

50 9. In a hydrogenation apparatus comprising a reaction chamber adapted to withstand high internal pressures, having an inlet and an outlet; a recirculating pipe directly connecting the outlet of said chamber to the upper end thereof.

55 10. In a hydrogenation apparatus comprising a reaction chamber, having an inlet and an outlet; a recirculating pipe connecting the outlet of said chamber to the upper end thereof; and a condenser surrounding the upper end of said recirculating pipe, 60 said pipe and condenser being so arranged that any condensate therein will flow into the chamber.

65 In testimony whereof I affix my signature.
